FISHLINE BOBBER

Adam P. Sowa, Grand Rapids, Mich.

Application October 20, 1948, Serial No. 55,473

2 Claims. (Cl. 43—15)

1

The present invention provides a system for the storage and release of energy. In its preferred form, this invention comprises a spring which is stretched to a given point and held in such position by the action of a trigger. Certain forces operate upon the trigger mechanism to effect the release of the energy stored in the spring. While a considerable variety of trigger-controlled mechanisms for the storage of spring energy have been developed, the present invention makes possible a simplicity of cocking action and construction which is not to be found associated with other devices of this general type.

The preferred form of this invention is embodied in the fish-line bobbers shown in the accompanying drawings. In these devices, the energy-storage system is utilized to set the hook the moment the fish disturbs the bait by applying the spring tension to the line as soon as the trigger system is actuated. Spring operated hook-setting devices are not new, but the use of the trigger mechanism provided by this invention creates several highly desirable characteristics of operation of the entire device which are not to be found in presently available equipment.

Preferably, the trigger is simply a piece of wire which is bent in a particular configuration. When the spring is in the cocked position, the spring force is resisted by the engagement of a particular portion of this bent wire with a fixed support associated with the housing to which the other end of the spring is attached. The curvature of the trigger wire is preferably such that tension applied between the lower end of the same and the opposite end of the housing causes the engaging portion of the trigger to come into cooperating relationship with the support and thereby lock the spring in extended position. The same action which extends the spring thereby serves to urge the trigger system into the engaged position. It is preferable that the fish-line leading from the bobber to the hook be attached to the trigger wire at a point somewhat remote from the engaging portion of the trigger in order to establish a considerable moment resulting from the action of the small forces applied by the fish to the hook.

The user of the preferred form of this invention illustrated in the drawings may cock the spring of the device by simply grasping the fish-line at either side of the device and pulling the same enough to stretch the spring to a point where the engaging portion of the trigger will cooperate with its support. The lower portion of the trigger wire is bent so that an angle is

2

formed by two lines: (a) a line passing through the upper point at which the bobber is connected to the fish-line, and through the point where the trigger connects to the spring, and (b) a line through the point where the trigger connects to the spring, and through the point where the trigger attaches to the fish-line. Tension on the fish-line applied through the device tends to cause this angle to straighten into a single line. The rotation of the wire with respect to the housing is limited by contact of the wire with the sides of the housing. At such point forces are generated which cause the engaging portion of the trigger to move into cooperation with the support as soon as such engaging portion reaches an appropriate position.

The various features of this invention will be analyzed by a discussion of the details of the particular device which is illustrated in the accompanying drawings. In these drawings,

Figure 1 shows a fish-line bobber embodying the present invention adapted to operate in a substantially vertical position, and

Figure 2 illustrates a bobber adapted to operate in a substantially horizontal position.

Referring to Figure 1, the bobber generally indicated at 10 is provided with the float 11 which maintains the device at the desired level with respect to the surface of the water 12. At the upper end of the device, the connecting point 13 is formed as a bent eye which accommodates the line 14 leading to the fish pole of the user. At the lower extremity of the device, a similar bent eye 15 is formed which accommodates the line 14a leading to the fish-hook assembly.

The central housing 16 of the bobber is provided with a suitable aperture at its upper end in which the member containing the bent eye 13 is secured. The inner portion of the housing 16 is formed as a hollow chamber 17 within which the spring 18 is contained. The lower portion of the housing 16 is provided with the aperture 19 which permits the movement of the trigger 20 into and out of the chamber 17 as the spring is cocked and released. A shoulder formed by the edge of the aperture 19 is used as the support point for the trigger. The vent 21 is provided in order that the air within the chamber 17 may not force the water within the chamber to a different level from that of the outside surface. Such a provision is desirable in order to maintain uniform buoyancy and stability to the device.

The trigger 20 is attached to the free end of the spring 18, and comprises an offset abutment 50 forming the engaging portion 22 which cooper-

ates with the edge of the housing 16 at the aperture 19 in order to maintain the spring in the extended position. The lower portion of the trigger 20 may be referred to as the cocking portion 23, and the portion of the trigger which is within the confines of the chamber 17 as shown in the drawing may be referred to as the stabilizing portion 24. It will be readily understood that tension applied to the line 14 and resisted by tension on the line 14a will cause the stabilizing portion 24 to move in a counterclockwise direction with respect to the housing as seen in the drawings. Such rotation will continue until the engaging portion 22 and the upper extremity 25 of the stabilizing portion contact the side of the chamber 17, and thereby prevent further rotation. When such contact has been effected, considerable force is generated which urges the engaging portion 22 and the support into cooperating relationship. The self-cocking feature results from the eye 15 being positioned at a point remote from a line projected along the axis of the stabilizing portion 24 and on the opposite side of that axis from the engaging point 22.

With the device as shown in Figure 1, the small movements of the fish at the bait cause the engaging portion 22 to gradually work into a position in which it snaps free of the edge of the housing and permits the tension of the spring 18 to be directly applied to the fish-line 14a, thus securely setting the hook.

Referring to Figure 2, a bobber is shown constructed substantially like the device illustrated in Figure 1, but in which an adjustment has been made causing the bobber to remain in approximately a horizontal position. This adjustment consists in moving the float 11 axially with respect to the housing 16, the adjustability being achieved by providing a sliding engagement between the two parts. If the float 11 illustrated in Figure 2 were to be moved to the left, the position of the center of gravity of the device with respect to the center of buoyancy would then tend to cause the bobber to move to the upright position illustrated in Figure 1. The position of the float along the housing required to cause the device to remain in the position shown in Figure 2 will be determined by the weight of the fish-line 14a between the bobber and the hook, and also the amount of weight which is used as a sinker, together with the weight of the fish-hook and bait. Any pulling at the bait by the fish will of course tend to cause the bobber to tip into an upright position and thus act to notify the user of the presence of the fish.

The action of the trigger 20 with the bobber disposed as shown in Figure 2 is slightly different from the action when the bobber is riding in the upright position shown in Figure 1. As a small pull is brought to bear upon the line 14a by the fish as it disturbs the bait, the cocking portion 23 of the trigger is deflected downwardly. This slight change in curvature of the wire causes the engaging portion 22 to slightly alter its angular relationship with the stabilizing portion 24. This alteration in angular relationship causes the engaging portion 22 to tend to assume a slight slope with respect to its associated supporting surface. This slope urges the engaging portion to slip off the support and thereby release the trigger. It will be noted that the curvature of the cocking portion 23 is such that the attaching eye 15 is placed a point considerably below the center of buoyancy of the device. The total weight of the fish-line 14a together with the weight of the sinkers, bait, and hook is therefore applied below

the center of buoyancy and tends to stabilize the device in "roll" and thereby insure that the direction of the action of the force on the line 14a remains as shown with respect to the location of the engaging portion 22.

It will be noted that the device shown in Figure 2 is provided with a connecting line between the attaching eyes 13 and 15. This connecting line is designated as 14b and it is preferably a portion 10 of the same line which extends from the pole of the user down to the fish-hook. The bobber 10 is thus connected in what may be called a "shunt" relationship with the section of the line 14b, which is selected to be of such length that tension between the sections 14 and 14a will not over-extend the spring 18 before the length 14b is drawn taut.

The device operating in the position shown in Figure 2, an action takes place which tends to increase the hook-setting action of the energy-storage system. As the trigger 20 is released, it begins an inward movement under the urging of the spring 18 guided by the walls of the chamber 17. As it proceeds along such inward movement, a point is reached where the lower portion 25 of the aperture 19 contacts the lower side of the cocking portion 22. As the trigger continues on its inward movement after such contact has been established, a counterclockwise moment is applied to the trigger due to the tendency of the cocking portion 23 of the trigger to become aligned with the housing as it moves inwardly, which tends to cause the connecting eye 15 to move upwardly and thus increase the hook-setting action of the spring. It will be appreciated that as soon as the fish has begun to nibble at the bait, the bobber assembly will tend to assume an upright position and the action of the spring moving axially along the chamber 17 will be applied substantially in a direction parallel to the line 14a.

The particular device which has been shown in the accompanying drawings and described herein is for illustrative purposes only and is not to be taken as a limitation on the scope of the appended claims. It is the inventor's intention 45 to claim the entire scope of the invention to which he is entitled in view of the prior art.

I claim:

1. A fish-hook setting mechanism comprising: first line-connecting means, spring means having one end connected to said first line-connecting means, a housing connected to said first line-connecting means and having a shoulder thereon remote from the connected end of said spring means, a flexible wire trigger attached at one end to the free end of said spring means and having an offset forming an abutment at an intermediate point adapted to cooperate with said shoulder for holding the force of said spring means, said trigger having freedom to move away from said shoulder to disengage said offset abutment therefrom, and second line-connecting means, said second line-connecting means being formed on the opposite end of said trigger from said spring, said abutment being disposed at a distance from a line connecting the ends of said trigger and adapted to engage said shoulder on the opposite side of said trigger from said line.

2. A fish-hook setting mechanism comprising: first line-connecting means, spring means having one end connected to said first line-connecting means, a housing connected to said first line-connecting means and having a shoulder thereon remote from the connected end of said spring means, a flexible wire trigger attached at one

end to the free end of said spring means and having an offset forming an abutment at an intermediate point adapted to cooperate with said shoulder for holding the force of said spring means, said trigger having freedom to move 5 away from said shoulder to disengage said offset abutment therefrom, and second line-connecting means, said second line-connecting means being formed on the opposite end of said trigger from said spring.
